UNITED STATES PATENT OFFICE.

WILLIAM M. BRUCE, JR., OF SPRINGFIELD, OHIO.

TELEGRAPHY.

1,369,218.

Specification of Letters Patent. Patented Feb. 22, 1921.

Application filed May 13, 1916. Serial No. 97,425.

To all whom it may concern:

Be it known that I, WILLIAM M. BRUCE, Jr., a citizen of the United States, residing at Springfield, in the county of Clark and 5 State of Ohio, have invented certain new and useful Improvements in Telegraphy, of which the following is a specification.

My invention relates to improvements in telegraphy and especially to systems operating upon lines where the resistance and capacity have a tendency to start the signals.

In sending Morse code over ordinary land line circuits it has been necessary to have repeaters owing to the polarization of line 15 and instruments, due to a larger charge of one polarity in making a long character or when spacing, even when reversals are used. Attempts have been made to overcome this by the use of transformers by which momentary impulses are applied to the line, but in such cases there being no current from 20 the transmitting station to hold the receiving relay in its operated position, this relay would be subject to outside disturbance such as power or other circuits in proximity to 25 other lines, also the breaking of the primary circuit in the transformer induces a circuit in the opposite direction which would effect the receiving relay and result in false signals.

In my improved system I employ momentary impulses of substantially equal duration at the beginning and end of the characters and impress these impulses upon the 35 primary of a transformer with the secondary of the transformer connected to the line and I further provide means for breaking the secondary at the same time the primary is broken and also apply a holding current 40 of the same polarity as the preceding induced current in the secondary and the line so that the receiving relay will be positively held in its operated position and not be disturbed by outside impulses or by the induced current of opposite polarity induced 45 by the breaking of the primary.

In my improved system I employ momentary impulses of substantially equal duration at the beginning and end of characters 50 which are of unequal duration and impart these impulses to a primary of transformer the secondary of the transformer being connected to the line and further provide means for applying a holding current of the 55 same polarity as the induced current in the secondary or line so that the receiving relay

will remain in its operated position and not be disturbed by outside influence.

The accompanying drawing is a diagram of circuits and apparatus which I have employed and which are illustrative of the invention herein described and claimed. In these drawings A represents an ordinary telegraph key which is connected in circuit with a relay A' whose armature moves between contacts A² and A³ which are connected to the opposite poles of a battery B. The armature A⁴ of this relay is connected to what I term the sending relay b by wire 1 which relay is connected by wire 2 to the 70 armature c' of a cut-off relay c, the armature c' of the cut-off relay c being arranged to move between contacts c² and c³ which are also connected to opposite poles of the battery B by wires 3 and 4. Each of the relays b and c are polarized relays and adapted to be moved in one position by a negative impulse and in the other position by a positive impulse from the battery B. The armature b' of the relay b also operates between 80 contacts b² and b³ which are connected to the opposite poles of the battery B by wires 5 and 6, the armature b' being also connected by wire 7 to the primary winding of a transformer T and thence by wire 8 to the armature c' of the cut-off relay c and to the opposite pole of the battery B by wire 4.

In the normal position shown it will be noticed that the armatures of the sending and cut-off relays are both resting against 90 contacts which are connected to the negative pole of the battery and no current is flowing. If the key A should be operated, the relay A' would be operated and move its armature A⁴ from the negative contact A³ 95 to the positive contact A² of the battery B. This would send a positive impulse to the sending relay b and would cause the armature b' of the sending relay to move to the positive contact b² and send a positive impulse of current through the primary of the transformer, the cut-off relay c being connected in parallel with the primary winding of the transformer would be operated by the same impulse but it is so connected or 105 constructed that it is operated at a predetermined time after the sending relay operates. I have shown inductive resistance r in circuit with this relay for the purpose. When relay c is operated it cuts off the current to the sending relay, also the current to the transformer and to itself and since its 110

armature is moved to the contact c^2 connected to the opposite pole of the battery all of the contacts will be with the positive pole of the battery and no current will flow. 5 As soon as the key A is released it breaks the circuit for the relay A' and its armature A' will return to normal position which will cause the armatures of the relays b and c to return to their normal positions with the 10 result that a negative impulse will be sent from the battery B to the primary of the transformer and the cut-off relay respectively, which negative impulse will be cut off after a predetermined time by the relay 15 c in the manner heretofore described and thus momentary impulses of opposite polarity will be impressed upon the primary winding of the transformer at each downward and upward movement of the key to 20 register the beginning and end of a character such as a dot or dash.

The secondary winding of the transformer is connected to the line under the usual duplex conditions by wire 9 and for each momentary impulse, negative or positive, a corresponding impulse is sent into the line and will operate the distant polarized relay on the main line in the usual manner.

Inasmuch, however, as these impulses that 30 operate the receiving relay are momentary, the relay might not be held in its operated position, and to overcome this I provide for placing a constant current of the same polarity upon the line as the previously induced impulse, preferably by applying the same to the secondary of the transformer and this is accomplished as follows:

The armature b' of the relay b is provided with an extension b^4 insulated from 40 the main portion thereof and this extension is grounded by wire 10 and it is adapted to play between contacts b^5 and b^6 which are also connected to the opposite poles of the battery B by wires 11 and 12, the poles, however, being reversed on these contacts from those on the contacts b^2 and b^3 of the armature so that when the main armature b' of relay b is resting on a negative contact the extension b^4 will be resting on a positive 45 contact and as the secondary winding is also connected by wire 8 to the armature c' of the cut-off relay c, which will be normally on a contact of opposite polarity, a circuit will be formed from earth through the extension armature through the battery and thence through the armature c' of the cut-off relay and the secondary winding and line to earth at the distant station thus holding the relay in its operated position. When 50 the relays assume their opposite positions the opposite pole of the battery will be grounded by the extension b^4 of the armature and an impulse of opposite polarity will be impressed on the line and the distant relay will remain in its operated position

until the relays b and c are again operated so that after each momentary impulse is transmitted to the line through the transformer, there will be a continuous current of the same polarity as the last induced impulse impressed upon the line to hold the distant relay in its operated position. 70

It will be observed that the circuit from ground at the sending station to ground at the receiving station, through the secondary 75 of the transformer and the line, passes through the wire 8 connecting the secondary to the armature c' and thence (in the position shown in the drawing) through contact c^3 , wire 4, battery B, wire 5, wire 12, contact b^6 , armature extension b^4 , wire 10 to ground at g. It will thus be seen that when cut-off relay c operates to cut-off the impulse to the primary of the transformer it also breaks the circuit for the secondary and no discharge in the line or in the current of opposite polarity due to the breaking of the current in the primary can occur to affect the distant receiving relay. This results in the distant receiving polarized relay being operated by impulses of high potential current and of momentary duration by means of the transformer, while the distant receiving relay is held in its position by a constant current supply of low potential which 90 does not polarize the instruments and lines to the extent that the high potential current necessary to operate the distant receiving polarized relay would.

In the normal condition as shown in the 100 drawings the line circuit to the distant receiving relay passes from ground g at the sending station through the shunt s, line 10, extension b^4 , contact b^6 , wire 12, wire 5 to battery B, wire 4, contact c^3 , armature c' , 105 wire 8, secondary of the transformer and line 9 with the holding current from the battery on the line. When the key is operated it transmits a sending impulse, this circuit will be broken at the contact b^6 and the ground applied through contact b^5 , wire 11, wire 6, wire 4, contact c^3 , armature c' , 110 wire 8, secondary of the transformer and line 9, the battery not being included in this circuit. At the same time this change is 115 made from contact b^6 to contact b^5 , the relay c will be operated, opening the shunt around the resistance r' thus including it in the ground circuit and compensating for the absence of the resistance of the battery in this 120 circuit during the momentary period before the cut-off relay operates to move its armature from contact c^3 to c^2 by which the battery will again be included in the circuit and the current for the relay c cut off and 125 the shunt around the resistance r' closed. This maintains constant conditions to received impulses from the distant station so as to avoid interference from duplex working. 130

Having thus described my invention, I claim:

1. In a system of telegraphy, the method of transmitting characters of unequal duration such as dots and dashes which consists in supplying from a battery to the primary of a transformer current impulses of opposite polarity and of substantially equal duration at the beginning and end of each 10 character and impressing the induced current impulses from the secondary of the transformer to a conductor to operate a distant translating device on said conductor by said induced or transformed current impulses substantially as specified.

2. The method of transmitting signals of unequal duration, such as dots and dashes, which consists in impressing impulses of opposite polarity upon one winding of a 20 transformer, inducing corresponding impulses in the other winding and impressing these upon a line, automatically cutting off these impulses so as to make them equal or of substantially equal duration and following each of said impulses by a holding current of the same polarity as the induced current.

3. In a system of telegraphy in which impulses of opposite polarity of equal or substantially equal duration are impressed upon 30 one winding of a transformer, inducing corresponding impulses in the other winding and impressing these upon a line, which impulses are followed by a holding current of the same polarity as the induced current, means for cutting off the holding current

before the succeeding impulses of opposite polarity are induced in the transformer.

4. In a system of telegraphy in which impulses of opposite polarity are impressed 40 upon one winding of a transformer, inducing corresponding impulses on the other winding and impressing these upon a line, which impulses are automatically cut off so as to make them of substantially equal 45 duration and followed by a holding current of the same polarity as the induced current, means for breaking the circuit of the induced current in one winding of the transformer at the same time that the impulse 50 impressed upon the other winding is cut off.

5. In a system of telegraphy in which impulses of opposite polarity and of substantially equal duration are impressed from a battery upon one winding of a transformer, 55 inducing corresponding impulses in the other winding and impressing these upon a line, which impulses are followed by a holding current of the same polarity as the induced current and which holding current 60 is cut off before the succeeding impulse of opposite polarity is induced in the line, means substantially as described for automatically introducing in the circuit resistance equal to the resistance of the battery 65 during the time the holding current is momentarily cut off the line.

In testimony whereof I have hereunto set my hand this 3rd day of May, 1916.

WILLIAM M. BRUCE, JR.
